UNITED STATES PATENT OFFICE.

CHARLES BOLLINGER, OF CHICAGO, ILLINOIS, ASSIGNOR TO WESTERN ELECTRIC COMPANY, INCORPORATED, OF NEW YORK, N. Y., A CORPORATION OF NEW YORK.

FURNACE.

Application filed March 13, 1925. Serial No. 15,212.

This invention relates to furnaces and more particularly to steam boiler furnaces, and has for its primary object the provision of an improved baffle wall and improved means for preventing silica slag formation upon the furnace walls adjacent the fire bed and grate.

In accordance with the general features of this invention there is provided in one embodiment thereof a flat baffle wall disposed above the fire bed and extending forward thereover from a bridge wall at one end of the fire bed. Embedded in the baffle wall are a plurality of steel pipes in the form of a coil through which water is circulated in the operation of the furnace. The coil structure functions to give rigidity to the baffle wall and due to the water circulating therethrough maintains it at such a temperature that any tendency thereof to disrupt or become deformed due to the intense heat is minimized. Disposed adjacent the fire bed along three sides thereof is a second coil composed of steel pipes which is connected to the first mentioned coil. In the operation of the furnace the water circulates from the boiler through the last mentioned coil, through the baffle wall coil and then back to the boiler. This circulation of water from the boiler through the several coils adjacent the fire bed tends to increase the heating surface of the boiler. The primary purpose of the coil positioned along the three walls of the furnace adjacent the fire bed is to maintain the walls at such a temperature as to prevent formation upon the walls of the furnace of any silica slag caused by the fusing of the fire brick lining due to the intense heat.

Other objects and advantages of the invention will more fully appear from the following detailed description taken in connection with the accompanying drawings which illustrate one embodiment thereof, in which—

Fig. 1 is a longitudinal vertical section through a water tube boiler furnace embodying my improvements;

Fig. 2 is a fragmentary vertical section taken on the line 2—2 of Fig. 1 looking in the direction indicated by the arrows;

Fig. 3 is a fragmentary plan section taken on the line 3—3 of Fig. 1 looking in the direction indicated by the arrows, and

Fig. 4 is an enlarged detail view of one

type of junction box provided for connecting the turns in the several coils.

Referring to the drawings illustrating a well known type of water tube boiler furnace, the parts of the furnace illustrated comprise, in general, a rear wall 10 and the side walls 11 and 12 comprising the usual brick construction common to furnace settings and 13 indicates a coking arch extending rearwardly and over the forward end 60 of the fire box or combustion chamber 14. A boiler tube bank of well known type is shown at 15. To the rear of the front wall (not shown) below the coking arch 13 and extending upwardly from the floor of the 70 furnace is a bridge wall 16. A traveling grate 17 is mounted within the fire box 14 in the form of an endless chain formed of a multitude of interconnected links, the upper portion of the grate forming the active 75 or fuel bed supporting area thereof. A drum is indicated at 18 which is suitably connected to a feed water supply.

In the construction of furnaces where the available space is limited and it is sometimes necessary to provide a boiler of a certain capacity it is necessary to build the baffle wall which extends forwardly of the bridge wall and integral therewith, which is indicated at 20, flat instead of arched, as is the 80 usual construction. To provide for sufficient rigidity in the flat baffle wall 20 there is provided a pipe coil 21 around which the usual type of fire brick is built, the pipe coil forming the necessary support for the 85 wall and, in the operation of the furnace, water is circulated through the coil which functions to reduce the temperature of the brick work within the arch and adjacent the coil without destroying the effectiveness of 90 the intensity heated outside surface thereof which functions to ignite the gases escaping from the fire bed. The cooling of the inside brick functions to reduce to a minimum any 95 tendency of the brick work to disrupt or become deformed.

Within the combustion chamber 14 adjacent two sides of the fire bed and at the rear thereof along the bridge wall 16 within suitable depressions 22 formed in the side 105 and bridge walls is a continuous coil of pipe 23 through which water from the drum 18 is circulated in the operation of the furnace. A vertically extending pipe 24 connected at its upper end to the drum 18 is 110

connected at its lower end with one end of a horizontally disposed pipe 25, the greater portion of which lies within the depression 22 in the side wall 11 of the furnace. The 5 right hand end of the pipe 25 (Fig. 3) is angularly formed and is extended through the side wall and is in communication with another pipe 27 lying within the same depression in the furnace wall and positioned 10 directly below the pipe 25, through a junction box 28 of the usual type. The pipe 27 is suitably connected at its left hand end (Fig. 3) with a laterally extending pipe 29 carried in the depression 22 formed in the 15 bridge wall. The pipe 29 is in turn connected with a pipe 30 carried in the depression 22 formed in the side wall 12. The pipe 30 at its right hand end is connected to another pipe 33 mounted in the same depression 20 22 as the pipe 30 and positioned directly thereabove. The connection between the pipes 30 and 33 is similar to that of the pipes 25 and 27. The left end of the pipe 33 is connected to a laterally extending pipe 34 positioned within the depression 22 and 25 above the pipe 29, the pipe 34 in turn being connected outside of the furnace wall 11 to a vertically extending pipe 35 (Fig. 1), the upper end of which is connected 30 to the inlet end of the pipe coil 21 embedded in the baffle wall 20, the outlet end of the coil 21 being connected to the water drum 18 by a vertically extending pipe 36. It will be observed, referring particularly to 35 Fig. 3, that each length of the horizontally disposed pipes forming the coils 21 and 23 is adapted to be readily cleansed of sediment and corrosion through the junction boxes 28 positioned without the walls of the furnace 40 and shown in detail in Fig. 4. The piping or tubes used in forming the coils 21 and 23 is preferably of the same size as the tube used in the boiler tube bank 15, thereby permitting the use of the ordinary cleaning 45 brushes or tools adapted to be used in the boiler tubes for cleaning the coils 21 and 23.

In the operation of the furnace, water circulating through the coil 23 functions to 50 draw a sufficient amount of heat from the walls of the furnace adjacent the slag line to prevent any fused silica formed by the intense heat upon the walls from flowing down the wall and forming an enlargement 55 of silica slag adjacent the fuel bed and grate which might in time interfere with the

proper operation of the moving grate and disturb the fire bed thereby reducing the efficiency of the furnace.

The combining of the coils 21 and 23 into 60 a single circulatory system connected to the water drum 18 results in an advantage other than that of simplifying the connections therefor and the means of supplying the necessary water to circulate therethrough, in 65 that the water circulating through the coils within the combustion chamber 14 actually increases the heating surface of the boiler, thereby adding to the efficiency of the furnace. 70

What is claimed is:

1. In a steam boiler furnace having side walls, a grate, a bridge wall extending between the side walls of the furnace and adjacent one end of the grate, a baffle wall, 75 and a sinuous chamber adapted to hold a cooling medium mounted in depressions formed in the bridge and side walls adjacent the top surface of the grate and also extended to and embedded within the baffle walls, the inlet and outlet ends of said chamber connected to a supply source of the cooling medium. 80

2. In a steam boiler furnace having side walls, a water drum, a grate, a bridge wall extending between the side walls of the furnace and adjacent one end of the grate, a baffle wall extending from the bridge wall and over the grate, and piping mounted in 85 pockets formed in the bridge and side walls adjacent the top surface of the grate and also extended to and embedded within the baffle wall, the inlet and outlet ends of said piping connected to said water drum. 90

3. In a furnace having a boiler tube bank 95 and side walls, a water drum, a grate, a bridge wall extending between the side walls of the furnace and adjacent one end of the grate, a baffle wall extending from the bridge wall and over the grate, a boiler tube 100 piping mounted in pockets formed in the bridge and side walls and also extended to and embedded within the baffle wall, said piping extended through the walls to the outside of the furnace and provided with a return loop, said outside portion adapted to be opened for the insertion of cleaning means, the inlet and outlet ends of said piping connected to said water drum. 105

In witness whereof, I hereunto subscribe my name this 5th day of March A. D., 1925. 110
CHARLES BOLLINGER.
